L'EXPLOITATION DES PROCEDES WESTINGHOUSE-LEBLANC, OF PARIS, FRANCE.

CONDENSING APPARATUS.

1,140,172.

Specification of Letters Patent.

Patented May 18, 1915.

Application filed September 15, 1909. Serial No. 517,844.

To all whom it may concern:

Be it known that I, MAURICE LEBLANC, a citizen of the Republic of France, and a resident of Croissy, in the Republic of France, have invented a new and useful Improvement Relating to Condensing Apparatus, of which the following is a specification.

In steam engines as now constructed and especially in those of the turbine type very little difficulty is encountered in preventing the entrance of air into the internal parts of the engine especially so when the exhaust mains leading from the engine to the condenser are short and the joints therein have been made with due care. In such cases it is found that only a small quantity of air will find its way into the condenser. In the case of an injection condenser, however, the condensing water continually conveys air, which has been dissolved therein when subjected to atmospheric conditions, into the condenser and this air becomes separated therefrom when the water passes into the vacuum chamber of the condenser. In order to obtain a high degree of vacuum in the condenser, it is necessary to extract from the condenser this comparatively large volume of air the amount of which is dependent upon the quantity of water introduced into the condenser.

It is of importance in all cases to reduce the volume of air to be extracted from the condenser and this result can be obtained by means of the improved air separator forming the subject matter of the present invention, the principal feature of which is the removal from the condensing water of the greater portion of the air which it has dissolved before the water passes into the condenser.

In the accompanying drawings, Figure 1 is a view in sectional elevation illustrating one form of the improved air separator. Fig. 2 is a similar view illustrating the invention as applied to a condenser. Fig. 3 is a view in sectional elevation showing the present invention as applied to a condenser of the parallel flow type. Fig. 4 is a similar view as applied to a condenser of the counter-flow type.

If, instead of introducing the condensing water directly into the condenser it is first passed in a finely divided state through an intermediate chamber, in which, for exam-

ple, a pressure of one fifth of an atmosphere is maintained, four fifths of the air which the water dissolved when exposed to atmospheric conditions will be separated from the water in the said intermediate chamber, consequently when the water passes into the condenser it will only introduce a fifth of the amount of air which it would have introduced if it had flowed directly into the condenser.

In the apparatus shown in Fig. 1, the intermediate chamber of the present invention is shown as constituted by a cylindrical tube 1 arranged in the interior of a cylindrical outer casing 2, the tube 1 being open at its lower extremity and arranged concentrically with the outer casing 2. The annular space between the tube 1 and the wall of the casing 2 is closed at one end by a flange carrying the tube 1, which is open at both ends. The casing 2 is provided with a nozzle 3 situated in its upper portion adapted to deliver the condensing water into the intermediate chamber in a finely divided state. An outlet 4 is provided located above the said chamber leading to an air pump adapted to extract the air separated in the chamber and so arranged as to maintain a constant pressure therein.

Adjacent to the flange of the tube 1 and on the under side thereof is an outlet 5 communicating with the condenser and adapted to supply the cooling water thereto as will be hereinafter explained. If a pressure of one-fifth of an atmosphere is maintained in the intermediate chamber, the water which will flow into this chamber through the nozzle 3 in a finely divided state will become separated from four-fifths of the air which it has dissolved, provided that the water is retained in the chamber for a sufficient length of time. In order that this result may be effected, it may be advisable, under some circumstances, to provide baffling plates in the interior of the chamber so as to prevent the water from passing from the nozzle 3 into the outlet pipe 5 in too short a space of time. The liquid separated from the air will accumulate at the bottom of the casing 2 until the pressure in the tube 1 is sufficiently greater than the pressure in the condenser to cause it to rise in the annular space between the tube 1 and the wall of the casing 2 to the level of the outlet pipe 5.

when it will flow into the condenser. The air which is released in the intermediate chamber will no longer pass into the condenser, but will be withdrawn by means of the air pump which is connected to the outlet 4 in the upper portion of the casing. The air pump of the condensing apparatus will thus be operating under considerably more efficient conditions since it will be discharging air at a materially higher pressure than that existing in the vacuum chamber of the condenser. In order, however, to produce a high vacuum in the condenser it will be necessary to remove the small quantity of air which still flows into the condenser with the condensing water by means of a special pump. Although the entire volume of air to be extracted from the condenser and also from the air separating chamber would be less than that which a single pump exhausting directly from the condenser would have to extract, it would not, under some circumstances, be advisable to employ two separate pumps. In such cases the air is extracted from the condenser and passed into the intermediate chamber from which it is subsequently withdrawn by means of the air pump. The volume of air to be extracted from the condenser is, as before explained, small and the compression which this air must be subjected to in passing into the intermediate chamber is materially less than would be the case if the air were discharged directly into the atmosphere, consequently the extractive power of the pump may be materially reduced.

If it is assumed that the pressure maintained in the intermediate chamber is one-fifth of an atmosphere, that is to say corresponding to a head of 2 meters of water, the condensing water will possess available energy when it arrives in the chamber and according to this invention this available energy is utilized to extract the air from the condenser and force it into the intermediate chamber. For this purpose a nozzle 6 is arranged above the tube 1 as shown in Fig. 2, the water arriving by the nozzle 3 operates as an ejector in passing through the nozzle 6 and withdraws the air from the condenser by means of passage 7 leading thereto. The cross-sectional area of nozzles 3 and 6 must be such that the water entering nozzle 6 from nozzle 3 will completely fill nozzle 6 or choke nozzle 6 in order that a higher pressure may be below the inlet to nozzle 6 than in the chamber above the same. The velocity of the water leaving nozzle 3 and entering nozzle 6 must be such as to entrain and carry the air from inlet 7 through nozzle 6 to the zone of higher pressure. The air which is thus withdrawn from the condenser is forced into the intermediate chamber from which it is subsequently withdrawn by means of the air pump connected to the outlet 4,

together with the air which is separated from the condensing water, as before explained.

The air separator of the present invention may obviously be applied to any type of condenser barometric or otherwise independent of the amount of air or steam admitted to the condenser, but is of course particularly adapted for use with injection condensers, as in this case its efficiency will be greater owing to the smaller quantity of air introduced with the steam as compared with that introduced with the water. In applying the air separator to a condenser where the amount of air introduced with steam is practically *nil*, it has been found from experiment that it is possible to reduce the pressure existing in the condenser to that corresponding to 22 millimeters of mercury when the condensing water enters the condenser at a temperature of 12° C. and is discharged at a temperature of 24° C. the pressure maintained in the intermediate chamber corresponding to 160 millimeters of mercury. To maintain the pressure in the chamber constant, the air is exhausted from the chamber by means of an air pump in the form of a simple steam ejector adapted to force the air thus withdrawn directly to the atmosphere as shown for example in Figs. 3 and 4. The steam employed with this ejector may be utilized to heat the feed water of the boiler.

In the arrangement shown in Figs. 3 and 4, the air is extracted from the intermediate chamber by means of a steam ejector 8, but it will be understood that the ejector may be replaced by an air pump of any suitable type, such for instance, as a water-jet air-pump of the Westinghouse Leblanc type, as set forth in Patent No. 984,278, dated February 14, 1911 and in some cases it will be advisable to employ an air pump instead of an ejector, particularly in cases where the amount of air admitted to the condenser with the steam is greater than the amount of air admitted with the condensing water.

In the parallel flow type of condenser illustrated in Fig. 3, the steam is admitted into the condenser at 9, the condensing water passing into the condenser through an annular water nozzle 10, and being removed by means of a centrifugal pump 11 in the well known manner. In this case the air is exhausted from the condenser by means of a small pipe 12 indicated in dotted lines leading to the pipe connection 7 of the air separator.

In the condenser illustrated in Fig. 4 the steam is admitted at 9, the condensing water issuing from the inlet 5 passes in cascade to the annular channel 10, thence to the lower portion of the condenser from which it is subsequently discharged by means of the outlet 4.

centrifugal pump 11. In this case the air passing into the condenser is withdrawn by means of pipe 12 connected to the passage 7 of the air separator as shown in dotted lines.

5 It will be understood that the invention is not limited to the particular construction and arrangement of the parts herein described and illustrated and various modifications may be made in the construction without exceeding the scope of the invention.

10 What I claim is—

15 1. The combination with a condenser, of a chamber for the reception of the condensing liquid, an inlet into said chamber adapted to admit the condensing liquid thereto in a finely divided state, an outlet for the condensing liquid leading from said chamber to the condenser, and means for extracting the air separated from the liquid in said chamber.

20 2. The combination with a condenser, of a chamber for the reception of the condensing liquid, an inlet into said chamber adapted to admit the condensing liquid thereto in a finely divided state, an outlet for the condensing liquid leading to the condenser, a connection between the condenser and said chamber and means for extracting the air from said chamber and from the condenser.

25 3. The combination with a condenser, of a chamber for the reception of the condensing liquid, an inlet into said chamber adapted to admit the condensing liquid thereto in a finely divided state, an outlet for the condensing liquid leading to the condenser, a connection leading from the condenser to said chamber, and means actuated by the condensing water admitted to said chamber for effecting the removal of the air from the condenser.

30 4. The combination with a condenser, of a chamber for the reception of the condensing liquid, an air extractor connected to said chamber, a connection between said chamber and the condenser, means actuated by the condensing liquid passing into said chamber for withdrawing the air from the condenser and forcing the same into said chamber, an outlet leading from said chamber, and means dependent upon the difference of pressure in the chamber and that in the condenser for effecting the passage of the condensing liquid through said outlet into the condenser.

35 5. The combination with a condenser, of a chamber maintained at a pressure less than atmospheric pressure, an inlet into said chamber for admitting the condensing liquid in a finely divided state, an outlet from said chamber leading to the vacuum chamber of the condenser, and means dependent upon the difference of pressure between the pressure in the chamber and that in the con-

40 denser for raising the condensing liquid above the level of the liquid in said chamber.

45 6. The combination with an injection condenser, of a chamber maintained at a pressure higher than that existing in the condenser, a connection between said chamber and the vacuum chamber of the condenser, an outlet from said chamber leading to the condensing water inlet of the condenser, an air extractor connected to said chamber, a nozzle for admitting the condensing liquid to said chamber, and a concentrically arranged ejector cone located in said chamber, operating in conjunction with the liquid admitted to said chamber to withdraw the air from the condenser.

50 7. The combination with a condenser, of a chamber maintained at a pressure higher than that existing in the condenser, a connection between said chamber and the vacuum chamber of the condenser, an outlet from said chamber leading to the condensing water inlet of the condenser, an air extractor connected to said chamber, a nozzle for admitting the condensing water to said chamber, a concentrically arranged ejector cone located in the upper portion of said chamber and arranged vertically below said nozzle, operating in conjunction with the condenser water admitted to said chamber to withdraw the air from the condenser and force the same into said chamber.

55 8. The combination with a condenser, of a chamber open at its lower extremity, a concentrically arranged outer casing surrounding the lower portion of said chamber forming an annular space between the wall of said chamber and the inner wall of said casing, an outlet in the wall of said casing leading to the condensing water inlet of the condenser, an outlet in said chamber leading to an air extractor, a connection between said chamber and the vacuum chamber of the condenser, an ejector cone attached to the wall of the chamber between the connection leading to the vacuum chamber of the condenser and the outlet leading to the air extractor, and a water nozzle for admitting the condensing water arranged vertically above said ejector cone.

60 9. Steam condensing apparatus comprising a condensing vessel, a separating vessel, a water chamber connected between the condensing vessel and the separating vessel, and means for causing the cooling water supply to draw air and incondensable vapors from the condensing vessel and convey the same to the separating vessel, said means including a pipe or passage arranged to become choked by water passing from the condensing vessel to the separating vessel.

65 10. Steam condensing apparatus comprising a condensing vessel, a separating vessel, a water chamber connected between the condensing vessel and the separating vessel, a

- suction pipe leading from the condensing vessel to the separating vessel, and a cold water supply forming with said suction pipe an aspirator whereby the cooling water supply draws the air and incondensable vapors from the condensing vessel, said suction pipe being arranged to become choked by water passing therethrough, and to automatically relieve itself of said water at a point above cold water supply.
11. Steam condensing apparatus comprising a condensing vessel, a separating vessel, a suction pipe arranged to become choked by water passing from the condensing vessel to the separating vessel, vacuum producing means connected to said separating vessel, a cooling water inlet to the separating vessel, and connections from the latter to the condensing vessel.
12. Steam condensing apparatus comprising a condensing vessel, a separating vessel, a suction pipe leading from the condensing vessel to the separating vessel, vacuum producing means connected to the separating vessel, and cooling water connections so arranged that the vacuum producing means maintains a sufficient head to cause the cooling water to enter the condensing vessel under all operating conditions of vacuum therein.
13. In combination with a condenser provided with a vacuum chamber for the reception of the fluid to be condensed, a preliminary chamber, means for causing a flow of cooling water for the condenser downwardly through said preliminary chamber, a water connection between said preliminary chamber and said condensing chamber constructed so as to form a double-legged water seal between said chambers; and separate air

exhausting means connected to said chambers and adapted to maintain a higher degree of vacuum in the condensing chamber than in the preliminary chamber.

14. In combination with a condenser provided with a vacuum chamber for the reception of the fluid to be condensed, a preliminary chamber, means for causing a flow of cooling water for the condenser downwardly through said preliminary chamber, a water connection between said preliminary chamber and said condensing chamber constructed so as to form a water seal between said chambers, and separate air exhausting means connected to the said chambers and adapted to maintain a higher degree of vacuum in the condensing chamber than in the preliminary chamber.

15. Condensing apparatus, comprising a main condensing chamber, a preliminary chamber for the cooling water, separate air exhausting means connected to the said chambers and adapted to maintain a higher degree of vacuum in the main than in the preliminary chamber, means for causing the cooling water to fall by gravity through the preliminary chamber, and a water passage connecting the two chambers and having water sealing legs which maintain a constant water seal under variations which may occur in the degrees of vacuum in the two chambers; substantially as described.

In testimony whereof, I have hereunto subscribed my name this thirtieth day of August 1909.

MAURICE LEBLANC.
